Des. 936

G. W. Sholl & Charles Stewart, of Cincinnati, O.
Letters Patent No. 936, Dated Aug. 25, 1857.

The schedule referred to in these Letters Patent, and making part of the same.

To all whom it may concern:

Be it known that we, G. W. Sholl & Charles Stewart, of the City of Cincinnati in the County of Hamilton and State of Ohio, have invented or produced a new and original design for an ornamental brick - and we do hereby declare that the following is a full and exact description thereof, referred being had to the accompanying drawings, and made to form part of this specification.

We don't confine ourselves to the usual size of bricks, but will make them from two to three feet long and other dimensions in proportion.

Fig: 1, of the accompanying drawings represents a face view of the brick ornamented with a group of flowers & leaves - the brick is chamfered on its edges, and when put together in a building they will form a raised panel.

Fig: 2, is a transverse sectional view of two of the bricks laid together, as a general thing they will be made hollow - as represented in Fig: 2, when made of an unusual size.

What we claim as our invention or production

Des. 936

and desire to secure by Letters Patent, is the combination of the ornamental design and configuration for a building brick - as represented in the accompanying drawings.
